COMB OR SIMILAR ARTICLE

Nicholas T. Baldanza, Rutherford, N.J., assignor to E. I. du Pont de Nemours and Company, Wilmington, Del., a corporation of Delaware

Application June 20, 1958, Serial No. 51,436

Term of patent 14 years

(Cl. D86—8)

Fig. 1

Fig. 2

Fig. 3

The dominant features of this design reside in the portions shown in solid lines in the accompanying drawing.

I claim:

The ornamental design for a comb or a similar article, substantially as shown and described.
